COMPARTMENT SHELF AND DIVIDER

Oliver M. Burkhart, East Moline, Ill.

Application May 3, 1939, Serial No. 271,589

5 Claims. (Cl. 211—135)

My invention has reference to a compartment shelf and divider, and is more specially designed for use in automobile compartments, such as are provided in the front of a vehicle, for the storage 5 of maps, gloves, and other small articles. These compartments usually contain a single space, and of limited dimensions, and when a number of small articles are placed therein, there is frequently difficulty in finding the ones wanted.

10 One of the purposes of the present invention is to provide a shelf of simple construction, which can be installed in a compartment, and divide the same into upper and lower spaces. In order to suitably support the shelf, plates are provided 15 extending downwardly into the lower space, and dividing the same into subspaces or compartments. A number of small receptacles are thus provided for the storage of various articles, by selection, and in convenient position for removal 20 when needed.

Another purpose of the invention is to have the supports, or partitions, connected with the shelf in such a manner that they can be adjusted in position longitudinally of the shelf, and not 25 only change the point of support of the plate, but also vary the sizes of the spaces in the lower compartment. Included therewith is a plate extension for the shelf, by means of which the length of the shelf can be adjusted, so that the same 30 may conform to compartments of different lengths. Resilient means is also provided for holding the shelf plates yieldably in place, so that they will fill the space for which they are intended.

35 The above named, and other features and advantages of the invention will more fully appear from the following specification, taken in connection with the accompanying drawing, in which:

Fig. 1 shows the invention in front elevation, 40 as it appears in place in a compartment.

Fig. 2 is a lower face view thereof.

Fig. 3 shows the parts of the invention in exploded view.

The reference number 6 indicates a fragmentary portion of a closure, such as the front wall or instrument board of an automobile, which closure is provided with an opening 7, fitted with a door 8, connected with the plate 6 by hinges 9, so as to open downwardly, as shown. Said door 50 is provided with a knob 10 for operation. This description relates to a construction common to automobiles, and in rear of the door is a space having end walls 11, forming a compartment for the storage of small articles, such as road maps, 55 gloves, and the like.

The invention consists of a shelf formed of plates 12 and 13, the latter of which is slidable on the plate 12, and guided by a rolled edge 14 on the plate 12, engaging the edges of the plate 13. The shelf thus formed is provided with a pair 5 of supports 15 and 16, the lower edges of which rest upon the floor of the compartment, and support the shelf at a desired height. The ends of the compartment are usually inclined a little, and the ends of the plates 12 and 13 are similarly 10 sloped.

The support 15 is formed of a sheet metal plate formed integrally with the plate 13, and bent downwardly at right angles therewith. The plate 16 has an angular flange 17 the ends of which 15 are slidable in the rolled edges of plate 12, with sufficient frictional engagement to hold the support 16 in adjusted positions. The position of the latter support can thereby be made to conform with that of the support 15, which is movable with the plate 13.

It will be observed that the plates 15 and 16 not only provide supports for the shelf, but that they form partitions or dividers for the space below the shelf, forming three spaces, or sub-compartments therein. These spaces, together with the space above the shelf, provide a number of receptacles for small objects, in which said objects can be conveniently distributed, so as to be easily located again when wanted. The plate 13 is held 30 yieldably in extended position by means of a spring 19, the ends of which are engaged with small recesses 20 of suitable size embossed in the rolled edges of the plate 12. Said spring is formed into a bend 21, engaged with a slit (not shown) 35 in the upper part of the support 15. Other pairs of recesses 20 are provided in the rolled edge 14, with which the ends of the spring can be selectively engaged, to vary the positioning thereof, and force of the spring.

To place the device in position in a compartment the supports 15 and 16 may be grasped by the hands, and the supports moved towards each other, as shown in broken lines in Fig. 2, reducing the length of the shelf, and permitting the 45 same to readily pass through the opening. The parts are then permitted to spread, by force of the spring 19, until the ends of the shelf come in contact with the ends of the compartment, against which they are tightly held, so as not to rattle. 50 If it is desired to remove the shelf this can be done by reversing the above operation.

The parts of the device are first formed in flat position, as shown in Fig. 3, in which position the plates can be packed together in a small space 55

for storage or shipment. When they are to be used the supports 15 and 16 are bent downwardly, and the parts assembled, ready for use.

Changes can be made in the construction and 5 arrangement of the parts of the invention without departing from the spirit of the invention.

What I claim, and desire to secure, is:

1. In combination with a closed compartment a pair of shelf forming plates having a slidable 10 adjustment with each other in contact at their ends with the end walls of the compartment, means for holding said plates yieldably in extended position, and means for the support of said plates connected therewith and forming sub- 15 compartments beneath said plates.

2. A device of the class described, comprising a plate having rolled edges, an auxiliary plate slid- 20 able in said rolled edges, a spring on one of said plates bearing against the other plate to hold the plates yieldably in extended position, and means for the support of said plates on the floor of a compartment.

3. A device of the class described, comprising a main plate having rolled edges at its sides, a 25 second plate slidable at its edges in said rolled edges, a plate support integral with said second

plate, a support having a flange slidable in said rolled edges, for adjustment on said main plate, and means for holding said plates yieldably extended.

4. A device of the class described, comprising 5 a pair of sheet-metal shelf-forming plates pro- vided with connections for slidable extensible and contractable movement with relation to each other, one of said plates having a part bendable at right angles therewith to form a support for 10 such shelf, and an auxiliary plate having a slid- able relation with the other of said plates, and having a part bendable at right angles therewith to provide an additional shelf support in parallel relation with said first named support. 15

5. A device of the class described, comprising a main shelf-forming plate, a pair of plates con- nected with said main plate for slidable move- 20 ment lengthwise thereof, and provided with an- gular plates forming shelf supports and dividing 20 the space beneath the shelf into smaller spaces, the adjustment of said supports with relation to each other effecting a variation in the sizes and proportions of the smaller spaces.
